ROLLER GRINDING MILL

George Jack, Rochelle Park, N. J., assignor to
 J. M. Lehmann Company, Inc., Lyndhurst, N. J.,
 a corporation of New York

Application June 9, 1950, Serial No. 167,140

6 Claims. (Cl. 308—60)

1

This invention relates to improvements in grinding mills of the type having a plurality of grinding rollers disposed in train with their axes in a single plane and parallel to each other with a feed and grinding roller offset from the plane of the other rolls, usually at one end thereof, and wherein the relative positions of the rollers are adjustable to vary the distance between them and also to change their operating pressures in order to adapt the mill for the treatment of different materials. Generally in a mill of this type, the roller at one end of the train is journaled in fixed bearings, while the bearings of all the other rollers in the train as well as the bearings of the offset feed and grinding roller are adjustable in relation thereto. Thus in a mill of this type having, for example, a train of four rollers in addition to the offset feed roller, as many as eight separate adjustments (two for the bearings of each roller) have sometimes been required to adapt the mill for treating a given material.

One of the objects of the present invention is to substantially reduce the number of bearing adjustments in such a mill, by eliminating the necessity for independently adjusting the positions of the rollers intermediate the top and bottom rollers of the train. Since the separate adjustment of these intermediate rollers requires the exercise of skill and judgment on the part of experienced operators, the elimination of the necessity for this saves both time and expense in mill operation.

Another object of the invention is to provide means whereby, once all the rollers have been adjusted to their desired operating positions and the mill has completed its run on one batch of material, the rollers of the train may be instantly separated to avoid injury to the surfaces of the rollers, so that the mill may be cleaned, and in order that the rollers may be readily returned to their already adjusted operating positions. The utility of the invention in the foregoing and other respects will appear more fully from the detailed description thereof which follows.

In the accompanying drawings, Figs. 1 and 2 are respectively a top plan and a side elevation of a 5-roller mill of the type referred to having four grinding rolls or rollers disposed in a vertical train and a feed and grinding roller offset at the bottom of the train; Fig. 3 a larger scale section taken on a plane indicated by the line 3—3 of Fig. 4; and Fig. 4 a front elevation thereof, partly in section and with some of the parts omitted for better illustration.

The mill shown in the drawings may be driven

2

by a motor 10 the shaft of which is belted to a pulley 11 fast on one of the journals of the top roller 12 of the vertical train of four rollers there shown. The bearings for each end of the roller 12, denoted generally by the numeral 13, are slidably mounted for vertical adjustment in the respective pairs of frame members 14, 14', one pair at each end of the mill. Of the other three rollers in the train, the bearings 15 of the bottom roller 16 are permanently fixed, as shown, to the end frame members 14, 14' while the bearings of the intermediate rollers 17 and 18 are slidably mounted for vertical adjustment in these end frame members, the same as in the case of the bearings of the top roller 12. The bearings of the lowermost roller 19 which is offset from the train and which, together with the bottom roller 16 of the train, constitute the initial feed and grinding rollers, are mounted in the frame, as shown, for horizontal adjustment toward and from the fixed bearings of the roller 16.

The rollers 17, 18, 16 and 19 are driven from roller 12, being operatively connected with one of the journals of that roller in such manner that roller 17 will rotate at slower speed than that of roller 12, the roller 18 at slower speed than that of roller 17, the roller 16 at slower speed than that of roller 18, and the roller 19 at slower speed than that of roller 16, so that when the mill is operated with the rollers in their operating positions each will have a rubbing contact with the adjacent roller or rollers to assist in reducing the material under treatment. This relative difference in the speed of rotation of adjacent rollers may be brought about by a train of gears, such as shown in Fig. 4, whereof the gears 20, 21, 22 and 23 are fast on the journals of the respective rollers 12, 17, 18 and 16 and mesh respectively with larger gears 24, 25 and 26 fast on the journals of the respective rollers 17, 18 and 16, and with a gear, which is not shown, on the journal of the roller 19.

Each bearing 13 of the roller 12 is linked to the bearing next below of the intermediate roller 17 by a pin 28, and each bearing of roller 17 is similarly linked to the corresponding bearing of the other intermediate roller 18 by a pin 29. For a purpose presently to be explained each of these pins 28, 29 is closely fitted to the lower of the two bearings which it connects but has a slight clearance, denoted in Fig. 4 by the numerals 28' and 29', with the upper of said two bearings.

For adjusting the bearings of the top roller 12 up or down in the frame members 14, 14' in order to adjust the position of that roller relative to

the fixed bottom roller 16 as well as to the other rollers in the train, means controlled by two hand-wheels 30, 30' are provided, one hand-wheel for each of the bearings 13. On each said hand-wheel is a worm 31 which meshes with a worm-nut 32 threaded to an eyebolt 33 firmly secured to the adjacent bearing 13 of the top roller. The shank of this bolt is free to move up and down in the hollow thrust-head 34 of a ram indicated at 35 and secured to the casing 36 which supports said adjusting means and is slidable on the mill frame. The nut 32 bears, at one side, against the thrust-head 34 and, at the other side, against the casing 36, so that when the hand-wheels 30, 31 are turned in one direction the bearings of the top roller will be moved downwardly to cause that roller to contact and press upon the intermediate roller 17 next below; and when the hand-wheels are turned in the opposite direction the pressure between these two rollers and between the other rollers of the column will be relieved and the rollers separated from each other.

Since the top roller adjusting mechanism just described is the subject of a pending patent application filed September 27, 1949, Serial Number 118,057, now Patent No. 2,592,048, dated April 8, 1952, no claim therefor is made here apart from its use in conjunction with the present improvements.

Assuming now that the relative positions of the four rollers in the vertical column are such that each said roller is in working relation with respect to its adjacent roller or rollers, and that the hand-wheels 30, 31 are turned in a direction to relieve the pressure between the rollers, this will not only raise the bearings of the top roller 12 but will also, in turn, cause the bearings of the intermediate rollers 17 and 18 to be raised by the linkage connections already referred to between these three sets of bearings. And since each of the pins 28 and 29 has a predetermined amount of free movement due to its aforesaid clearance with one or the other of the bearings connected thereby, it will be apparent that the top roller 12 may be adjusted away from the next intermediate roller 17 by a predetermined amount, say $\frac{1}{16}$ of an inch, before the adjusting movement of the top roller affects said roller 17; but that by continuing the upward adjusting movement of the top roller the intermediate roller 17 will be caused to separate from the next intermediate roller 18 by a predetermined amount, say also $\frac{1}{16}$ of an inch; then, by a still further upward adjusting movement of the top roller, the intermediate roller 18 will be caused to separate from the fixed bottom roller 16 by a predetermined amount, say again $\frac{1}{16}$ of an inch. Hence, when the top roller has been adjusted away from the fixed bottom roller 16 by a total of $\frac{1}{16}$ inch, there will then be a clearance of $\frac{1}{16}$ of an inch between each of the rollers 12, 17, 18 and 16. Conversely, when, with these rollers in their open or separated positions, the hand-wheels 30, 31 are turned in a direction to readjust the mill to its operating condition again with all these rollers in working relation to each other, the uppermost three rollers will move downward together as a unit until the intermediate roller 18 assumes its working relation to the fixed bottom roller 16 and stops; then the two uppermost rollers will move as a unit until the intermediate roller 17 assumes working relation to the intermediate roller 18 and stops; and finally the top roller 12 will move alone until it

assumes working relation to the intermediate roller 17. Further adjustment of the top roller toward the fixed bottom roller 16 will now cause pressure to be applied between the working surfaces of these four rollers, the degree of which is registered by two pressure gauges 37 (Fig. 2) communicating respectively with the cylinders of the rams 35. When these gauges register the degree of pressure desired between said rollers for the treatment of any given material, the mill, so far as the rollers 12, 17, 18 and 16 are concerned, is ready for operation upon that material.

It will be understood by those skilled in the art that the adjustment of the rolls toward working relation to each other is carried out when the surface of at least one of the rolls is covered with material to be treated, thereby avoiding injury to the roll surface due to the speed differential between surfaces which would otherwise be in contact.

After the mill has completed its run on any batch of material and it is desired to make a new run of the mill on material of a different nature, the mill will ordinarily need to be cleaned to remove all traces of the previously treated material. For this purpose it is desirable that the rollers be separated sufficiently to make all the parts accessible for thorough cleaning; and where the new run is to be made with the same roller adjustment as before, it is also desirable that means be provided for instantly separating the rollers 12, 17, 18 and 16, that is, without resort to the adjusting means already described, and then instantly returning them again to their previously adjusted positions. Accordingly, each bearing 13 of the top roller 12 is provided with a rotatable member 38 carrying a cam 39 which is embraced by the eye of the bolt 33 aforesaid, so that by a partial rotation of the members 38, each of the bearings 13 of the top roller may be instantly raised, together with the bearings of the intermediate rollers 17 and 18 through their linkage connections with the bearings of the top roller. This will cause all of the rollers in the train to be separated from each other and thus provide a sufficient clearance between them for cleaning. The rotation of the members 38 may be effected by a bell crank lever 40 fulcrumed at 41 and connected by links 42 to crank arms 43 respectively provided on the rotatable members 38. As shown in Fig. 2, the swinging of this lever through an arc of about 120 degrees from its full line position to its broken line position in that figure will cause the instant separation of the rollers; and the swinging of this lever back to its full line position will instantly return the rollers again to their operating positions without necessitating any readjusting of their relative positions by the hand-wheels 30, 31.

The proper adjustment of the offset feeding and grinding roller 19 relative to the bottom roller 16 of the vertical column may be effected by adjusting means substantially the same as the adjusting means described aforesaid for the bearings of the top roller 12, and which, as aforesaid, is the subject of the pending patent application filed September 27, 1949, Serial Number 118,057 above mentioned. This adjusting means which is applied to each of the bearings of the roller 19 may be similarly operated by two hand-wheels 45, 45' and will be understood without further explanation.

Thus a 5-roller mill of the type shown in the drawings and which, as heretofore constructed,

sometimes required eight separate roller adjustments to accurately position the rollers for operation, may, in accordance with the present improvements, have all its rollers positioned for practical operation by only four roller adjustments which are accomplished through the four hand-wheels aforesaid in the manner above described. In former 5-roller mills built with eight hand-wheels, one pair for each adjustable roller, the manipulation of one pair of hand-wheels to adjust the position of one of the intermediate rollers of the train will obviously affect the setting of the adjacent roller or rollers; and it is because of this that adjustment of a 5-roller mill as so constructed is extremely difficult for an inexperienced operator; and great care and good judgment have always been necessary to obtain optimum results from the operation of such mills. The present improvements make it possible to adjust a mill for its best performance in far less time and by operators who have not had long experience and do not possess the best of judgment. In short, the precision of adjustment required for 5-roller mill operation is, so to speak, built into the mill by the incorporation of the present improvements, thus leaving only a relatively simple primary adjustment for the operator.

It may be observed, however, that the use of the improvements thus far described herein would not result in providing substantially equal pressures between the rollers 12, 17, 18 and 16 when the mill has been adjusted to its operating condition by the adjustment aforesaid of the top roller. The reason for this is that the pressure between the intermediate rollers 17 and 18 would normally exceed the pressure between the top roller and the roller 17 by the weight of the roller 17, and that the pressure between the intermediate roller 18 and the bottom roller 16 would normally exceed that between the intermediate rollers 17 and 18 by the weight of the roller 18. In the treatment of most materials this pressure differential would not be detrimental to mill operation but in the case of a few materials it might be. Accordingly, the present improvements include means whereby, if desired, the pressures between the different rollers in the vertical column may be equalized. These means consist in the provision of spring supports for balancing or overcoming the weight of the intermediate rollers 17 and 18 respectively. As embodied in the mill shown in the drawings, such spring supports are provided by levers 46 and 47 fulcrumed to the mill frame at 46' and 47' respectively; the upper arms of these levers are substantially horizontal and bear directly upon the pins 28 and 29 respectively, while their lower arms which are substantially vertical are urged inwardly by compression springs 48 and 49. These springs are adjustable so as to impart to the pins 28, 29 precisely the amount of upward pressure required to balance the weight of the respective intermediate rollers 17 and 18. The adjustment of these springs will ordinarily be made at the factory; and once adjusted, they require no further adjustment or attention by an operator.

The provision of these spring supports has the further advantage that when the top roller is raised or adjusted to release the pressure, the springs will tend to lift the intermediate rollers 17 and 18 and cause separation between the rollers 17, 18 and 16. In treating some materials of extremely low viscosity and tackiness, the roller pressures should be accurately proportioned or set exactly the same between each pair of rollers.

5 In cases of this nature, it will be understood that the springs 48 and 49 may be so adjusted as to make the intermediate rollers 16 and 17 practically weightless or just floating in operative position.

6 Bearing in mind that the several rollers are geared to be driven at different speeds usually at increasing relative speeds from the feed roll through the train to the top roller, it will be apparent to those skilled in this art that injury to the roll surfaces may very well take place if they are run dry, that is to say, without any treated material passing through the mill. If therefore the rolls are not quickly separable by throwing the lever 40 when the supply of material passing through the mill is exhausted, injury to the roll surfaces may result and it is for this reason that the spring supports are valuable in conjunction with the former taking up any lost motion in the latter and making it easier to lift the upper and two intermediate rollers.

In operating the mill shown in the drawings, the material to be treated is delivered into a hopper 50 (Fig. 2) which feeds the material between the rollers 16 and 19. As these rollers revolve, the material which passes between them adheres to the surface thereof and continually passes successively from the roller 16 to each of the rollers above in the vertical column until it reaches the top roller 12 from the surface of which it is scraped by a knife (not shown) on the inner edge of a receiving pan or discharge chute 51 (Figs. 1 and 2) into which the scraped-off material drops. This feature of the mill constitutes no part of the present invention nor does the water cooling system for the rollers, a part of which is indicated by a pipe 52.

I claim as my invention:

40 1. A roller grinding mill comprising a plurality of rollers disposed one above another in a substantially vertical train, a bearing at each end of each roller, frame members at each end of the mill in which all said bearings but those of the bottom roller of the train are slidable, means to adjust the position of the top roller of the train relative to the bottom roller of the train, and means to link the slidable bearings together comprising pins each of which connects an adjacent pair of these bearings and is closely fitted to one of said pair but has a clearance with the other of said pair.

45 2. A roller grinding mill comprising a plurality of rollers disposed one above another in a substantially vertical train, a bearing at each end of each roller, frame members at each end of the mill in which all said bearings but those of the bottom roller of the train are slidable, means to adjust the position of the top roller of the train relative to the bottom roller of the train, and 50 means to link the slidable bearings together comprising pins each of which connects an adjacent pair of these bearings and is closely fitted to the lower bearing of said pair but has a clearance with the upper bearing of said pair.

55 3. A roller grinding mill comprising a plurality of rollers disposed one above another in a substantially vertical train, a bearing at each end of each roller, frame members at each end of the mill in which all said bearings but those of the 60 bottom roller of the train are slidable, means to adjust the position of the top roller of the train relative to the bottom roller of the train, and means to link together respectively the slid- 65 able bearings in each end frame member the 70 said last named means having spring supports

to balance respectively the weights of each roller of the train intermediate the top and bottom rollers of the train.

4. A roller grinding mill comprising a plurality of rollers disposed one above another in a substantially vertical train, a bearing at each end of each roller, frame members at each end of the mill in which all said bearings but those of the bottom roller of the train are slidable, means to adjust the position of the top roller of the train relative to the bottom roller of the train, and means to link together respectively the slideable bearings in each end frame member the said last named means having spring supports to balance respectively the weights of each roller of the train intermediate the top and bottom rollers of the train, each said spring support comprising a lever, one arm of which is operatively connected to one of the bearings and a spring applied to the other arm of the lever to impart an upward pressure of the first named arm.

5. A roller grinding mill comprising a plurality of rollers disposed one above another in a substantially vertical train, a bearing at each end of each roller, frame members at each end of the mill in which all said bearings but those of the bottom roller of the train are slidable, means to adjust the position of the top roller of the train relative to the bottom roller of the train, means to link together respectively the slideable bearings in each end frame member, and spring supports to balance respectively the weights of each roller of the train intermediate the top and bottom rollers of the train, and in which the means to link the slideable bearings together comprise pins each of which connects one of the slideable bearings to the slideable bearing next below it, and each said spring support comprising a lever one arm of which contacts one of the connecting pins, and a spring applied to the other 40

arm of the lever to impart an upward pressure to that said pin and through said pin to the bearing below it.

6. A roller grinding mill comprising a plurality of rollers disposed one above another in a substantially vertical train, a bearing at each end of each roller, frame members at each end of the mill in which all said bearings but those of the bottom roller of the train are slidable, means to 10 adjust the position of the top roller of the train relative to the bottom roller of the train, means to link together respectively the slideable bearings in each end frame member, and spring supports to balance respectively the weights of each 15 roller of the train intermediate the top and bottom rollers of the train, and in which the means to link the slideable bearings together comprise pins each of which connects one of the slideable bearings to the slideable bearing next below it, 20 and each pin being closely fitted to the said bearing next below but having a clearance with the other said bearing, and each said spring support comprising a lever one arm of which contacts one of said connecting pins, and a spring applied to the other arm of the lever to impart an upward pressure to said pin and through said pin to the lower of the two bearings which it connects.

GEORGE JACK.
